UNITED STATES PATENT OFFICE.

GEORGE ALBERT CRITCHERSON, OF LOS ANGELES, CALIFORNIA, ASSIGNOR TO THE COLUMBUS DENTAL MANUFACTURING CO., OF COLUMBUS, OHIO, A CORPORATION.

RUGÆ-MOLD FOR DENTURE-PLATES.

1,183,540.

Specification of Letters Patent. Patented May 16, 1916.

Application filed January 2, 1915. Serial No. 451.

To all whom it may concern:

Be it known that I, GEORGE A. CRITCHERSON, a citizen of the United States of America, residing at Los Angeles, in the county 5 of Los Angeles and State of California, have invented certain new and useful Improvements in Rugæ-Molds for Denture-Plates, of which the following is a specification.

10 This invention is an improvement on the rugæ mold disclosed in my application originally filed November 22, 1913, Serial No. 802,452 and now claimed in divisional application filed May 1, 1914, Serial No. 835,669.

15 Heretofore in the manufacture of denture plates they have been molded with an upper surface to fit the rugæ or undulations of the roof of the mouth, but with a smooth surface for the under or lingual surface of the 20 plate, or artificial roof of the mouth, which results in imperfect articulation and in imperfect management of food in mastication, because when the under surface, or lingual side, of the plate is smooth the tongue has 25 but little power to hold or manipulate a morsel of food upon it.

As in the rugæ mold heretofore invented by me the mold forming the subject matter 30 of this invention is formed with a natural rugæ, but no claim is herein made for this *per se* as that feature is claimed in my former application.

The object of my present invention is to provide a rugæ mold of metal in proper 35 form and of a thickness sufficient to hold the corrugations or undulations constituting the rugæ mold, while the outer marginal edge portion of the metal of the mold is much thinner than the portion in which the rugæ 40 is formed, whereby said marginal portion more readily lends itself to the work of burnishing and adjusting to the entire surface of the plate and between the teeth so that no polishing or burnishing of the denture plate will have to be done after the 45 rugæ molds have been removed from the vulcanized plate.

In the drawings: Figure 1 is a plan view of the lingual side of a denture plate with 50 my improved rugæ mold burnished in posi-

tion thereon. Fig. 2 is a plan view of the lingual side of the rugæ mold detached. Fig. 3 is a plan view of the lingual side of a rugæ mold as it is furnished to the trade. Fig. 4 is a vertical sectional view on the line 55 4—4 of Fig. 3.

The reference numeral 5 designates a denture plate and 6 teeth secured thereto. The rugæ mold 7 is composed of metal, or any other suitable material, the middle portion 60 of which is much thicker than the marginal portion 8. In other words the mold is made of different thickness in different portions of its area. The middle or interior portion of metal in which a natural rugæ is formed 65 must be of sufficient thickness to maintain the formation given it in forming therein the corrugations or undulations constituting the rugæ, while the marginal portions of the metal should be relatively thinner than the 70 middle portion, so as to lend itself to the work of burnishing and adjusting the rugæ to the entire surface of the plate, and burnishing and adjusting the marginal portions between the teeth as 75 shown in Fig. 1. When the mold has been thus burnished and adjusted on a plate, it is not necessary to polish or finish the plate after the mold has been removed. The relatively thin marginal portion of the 80 mold enables me to readily burnish it up to and between the teeth whereby it may be adapted to the individual case.

In using this invention the dentist waxes up as usual, and has the base plate of the 85 same thickness on palatal portion of the base plate as the desired thickness in the finished plate. Just before flasking place a rugæ mold upon the base plate in correct relation to the teeth, not forcing it into the base 90 plate, but with a comparatively soft implement press around the edges gently pressing the mold in place. After the plate has been flasked and vulcanized and the mold removed from the plate it will be found that 95 it will not be necessary to polish the plate. When the rugæ mold has been removed it will have the configuration shown in Fig. 2, the pointed portions 9 having extended between the teeth, while the tongues 10 at the 100

rear have been fitted around the back of the last tooth of the plate.

What I claim is:

A rugæ mold comprising a relatively thick middle portion having the formation of a natural rugæ, and a relatively thin marginal portion.

Copies of this patent may be obtained for five cents each, by addressing the "Commissioner of Patents, Washington, D. C."

In testimony whereof I affix my signature in presence of two witnesses.

GEORGE ALBERT CRITCHERSON.
